TOY GUN

Robert A. Charvat, Bay Village, Ohio, assignor to American Arts & Crafts, Inc., Columbus, Ohio, a corporation of Ohio

Application November 7, 1955, Serial No. 545,265

5 Claims. (Cl. 46—227)

My invention relates to a toy gun. It has to do, more specifically, with a toy gun provided with a translucent or transparent barrel and in which the movement of a projectile is simulated by a series of electric light bulbs spaced along the barrel which are illuminated rapidly and successively from the rear of the barrel to the front end thereof by the pulling of the trigger.

In the accompanying drawings, I have illustrated examples of my invention. In these drawings:

Figure 1 is a vertical sectional view through a toy pistol in which my invention is embodied.

Figure 2 is a bottom plan view of a switch bar used in the gun of Figure 1.

Figure 3 is a side elevational view of a contactor wire used in the pistol of Figure 1.

Figure 4 is a top plan view of the wire.

Figure 5 is an enlarged horizontal sectional view taken on line 5—5 of Figure 3.

Figure 6 is a view similar to Figure 2 but showing a contact finger in contact with the switch bar.

Figure 7 is a detail in side elevation of the trigger mechanism of the pistol of Figure 1 showing the side opposite to that shown in Figure 1.

Figure 8 is an end view of the mechanism of Figure 1.

Figure 9 is a diagrammatic view in side elevation showing a modification of the mechanism of my invention.

With reference to the drawings, I have illustrated in Figure 1 my invention embodied in a pistol. However, it is not limited to a pistol but is applicable to other types of guns and toys where light sources can provide various effects.

The pistol is shown as comprising a body section which is preferably formed of translucent plastic. The body is preferably formed of two half sections, one being the section 10 shown and which carries all the mechanism, and the other being a cover body section (not shown). Clips 10a and 10b are provided on the body section shown for use in removably attaching the two body sections together. Along the barrel section of this body section I provide a series of axially spaced light bulbs 11, 12, and 13 although a different number of these bulbs may be provided. These bulbs are removably held in position by integral plastic fingers 14 for each bulb. The lower contact portions of the bulbs 11, 12, and 13 are always in contact with a ground bar 15 which extends through the lower portion of the barrel section and back into the handle section where it terminates in an upstanding spring contact finger 16. The bar 15 is held in fixed position by means of the anchoring pins 17.

A battery of the flashlight type is removably held between the spring contact finger 16 and a switch bar 19. The switch bar 19 is anchored to the pistol body section by means of the anchoring pins 20. This switch bar 19 is shown in Figures 1 and 2 and includes a resilient spring finger 21 which extends forwardly and is angled laterally relative to the axis of the pistol barrel section, as shown in Figure 2.

Cooperating with the switch bar 19 to make contact

2

at the proper intervals for lighting the bulbs 11, 12, and 13 successively is the contactor wire 22 which is mounted for sliding movement axially of the barrel section in the lugs 23 attached to the wall thereof, so that it will be held in sliding contact with the sides of the bulb contact portions as indicated in Figure 1. This contact wire 22 is shown in Figures 1, 3, 4, 5, and 6. The wire 22 is coated with a suitable non-conductive coating, for example, of plastic. A suitable coating is "Formvar" manufactured by General Electric Company. This coating is removed at three intervals along the length of the wire as indicated at 11a, 12a, and 13a in Figures 3 and 4.

For reciprocating the contactor wire 22, a trigger-actuated cylinder piston and spring tension unit is provided which includes the piston 25 that reciprocates in the cylinder 26 and extends from the forward end thereof. The cylinder 26 is anchored in place in the handle section of the pistol by means of the lugs 27. The piston 25 is provided with a laterally-turned forward end 28 about which the rear end of the contactor wire 22 is coiled, as shown in Figure 4. This coiled portion is provided with an upstanding contact finger 29 which is shown in Figures 1, 3, 5, and 6. This finger is coated with plastic except that it is removed from the one side, which will be the back side in Figures 1 and 6.

The piston 25 is normally held in its forward position by means of a tension spring 30 (Figure 7) which is anchored at its front end to a pin 31 on the body section and has its rear end connected to the lateral end 28 of the piston. Thus, since the piston 25 is normally held in its forwardmost position, the contactor wire 22 (Figure 1) connected thereto is also held in its forwardmost position.

To move the piston 25 rearwardly against the action of the spring 30, I provide the trigger mechanism including the trigger 32 (Figures 1 and 7) that is slidably mounted on the body section in association with a trigger guard 33. This trigger 32 is provided with an upstanding pawl lug 34 at its rear upper corner to which a trigger pawl 35 is pivoted at 36 for vertical swinging movement. The pawl 35 extends forwardly beneath the piston 25 and its forward end is provided with an upstanding tooth 37. A tension spring 38 has its rear end connected to the front end of the pawl 35 and its front end anchored to a pin 39 carried by the body section 10. Normally, with the trigger 32 and the pawl 35 pivotally carried thereby held in rearwardmost position by the spring 38, the tooth 37 is in engagement with the forward side of the lateral end 28 of the piston 25 as shown in Figures 1 and 7.

As the trigger 32 is pulled rearwardly, the piston 25 is drawn rearwardly against the action of the springs 30 and 38. The pawl tooth 37 will engage the end of the piston 25 to pull it rearwardly until a cam surface 40 at the forward end of the pawl, strikes the forward end of the cylinder support 27, at which time the pawl will swing downwardly so that it will be released from the piston 25 and the spring 38 will then pull the piston forwardly back to the original rest position shown in Figure 1. The pawl is provided with a rearward extension 41.

As the piston 25 is drawn rearwardly, the contactor wire 22 is pulled rearwardly along with the upstanding finger 29 thereof. The finger 29 is so located that when it moves rearwardly its coated side contacts the inner side of segment 21 of the switch bar 19 and snaps around the rear end of the segment 21. Now when it moves forwardly its bare side contacts the outer side of the bar, as shown in Figure 6, and connects the battery 18 with the contactor wire 22. As the finger 29 moves off the forward end of the segment 21 it again snaps inwardly so that when moved rearwardly again it will engage the inner side of the segment 21.

As the trigger 32 is pulled rearwardly the pawl extension 41 engages the upper free end of a sound-pro-

ducing spring 45. This spring 45 is a flat spring which is anchored at 46 at the lower end of the handle section. When the upper vertical end 47 thereof is engaged by the pawl extension 41, the spring 45 is bent rearwardly, but as soon as the trigger is released, the spring will snap forwardly and will vibrate to produce a sound.

In the at rest position of the contactor wire 22 shown in Figure 1, none of the bulbs are lighted because the circuit is open due to the fact that the contact finger 29 is not in contact with switch segment 21. Likewise, the bulbs are not lighted while contactor wire 22 is being moved to the rearward position because finger 29 is behind the switch bar segment 21 (Figure 1) in which position the plastic insulating material on the finger 29 separates these two circuit elements. However, after contactor wire 22 is pulled rearwardly by pulling the trigger and the trigger releases the moving part of the mechanism, wire 22 moves forwardly so that the bare sections 11a, 12a, and 13a are rapidly brought in succession into contact with the contact portions of the bulbs 11, 12, and 13. At the same time, finger 29 is on the front side of the switch bar segment 21 (Figure 6) in which position electrical contact is made because the bare side of the finger is in contact with the switch bar segment 21. The bare sections 11a, 12a, and 13a will be accurately disposed so that a circuit to each bulb will be completed successively and the bulbs will be lighted at successive intervals. Since the barrel of the pistol will be translucent or some equivalent, this will give the illusion of a projectile passing through the barrel. On the rearward movement of the trigger none of the bulbs are lighted but on the forward movement all the bulbs are lighted in rapid succession.

In Figure 9, I have illustrated a modified arrangement of my invention. In this figure the connector wire 22b is in contact with the same sides of the bulbs 11b and 13b and the opposite side of the bulb 12b. A ground bar 15b is associated with the bulbs as before. The piston 25b and the cylinder 26b are reversed and the spring 30b draws the piston rearwardly. The contact finger 29b is arranged to engage the switch bar 19b, connected to the battery 18b, on the rearward movement of the piston so that the connector wire 22b will successively complete the circuit from the battery 18b to each of the bulbs 11b, 12b, and 13b. The battery 18b is connected by a connector 50 to a buzzer 51, the connector 50 being also connected to the ground bar 15b. Another connector bar 52 extends from the battery and terminates along the switch bar 19b. The end of this bar 52 is disposed along the switch bar 19b so that the finger 29b will slide rearwardly therealong at the same time that the finger slides along the switch bar 19b. Thus, when the piston 25b moves rearwardly, a circuit to the buzzer and also to the bulbs 11b, 12b, and 13b is completed, the bare spots on the connector wire 22b being arranged to light the bulbs successively. The pawl and trigger arrangement will be substantially

as before, the pawl 35b engaging the turned end 28b of the piston 25b on the rearward movement of the trigger until it is released to permit the rearward movement of the piston with the connector wire 22b. This rearward movement, as indicated, will successively light the bulbs 11b, 12b, and 13b and simultaneously operate the sound buzzer 51.

It will be apparent that I have provided a toy gun in which movement of a projectile or energy is closely simulated without the dangers present when actual projectiles are used. Furthermore, I provide noise-making means in the gun which makes it more realistic.

Having thus described my invention, what I claim is:

1. A toy gun of the type described comprising a translucent barrel having a series of light bulbs and associated contacts supported at intervals therealong, a source of electric current, means for connecting said light bulb contacts successively to said source of current, said means comprising a contact wire mounted for reciprocation in engagement with said contacts of said light bulbs, said wire being coated with an insulating coating but having the coating removed at areas which will successively contact said contacts of successive bulbs at intervals, and trigger mechanism operatively connected to said contact wire to produce reciprocation thereof.

2. A toy gun according to claim 1 in which said means for connecting the light bulb contacts to the source of current includes a switch bar and a switch finger movable on opposite sides of said switch bar upon reciprocation of said wire, said switch finger being coated with an insulating coating on one side only so that it makes electric contact with said bar in one direction of movement only, and means for reciprocating said contact wire and said switch finger simultaneously.

3. A toy gun according to claim 2 in which said reciprocating means comprises a piston, said trigger mechanism comprising means for pulling the piston rearwardly and then releasing it, and a spring for returning the piston to its original position.

4. A toy gun according to claim 3 including noise-producing means actuated upon the return movement of said piston, said noise-producing means comprising a vibrating spring engaged by said trigger mechanism.

5. A toy gun according to claim 3 including noise-producing means comprising an electric alarm device, connected to said source of current, and means actuated by said piston for completing the circuit to said device.
